REFLEX REFLECTOR

Morris Kaplowitz, Brooklyn, N. Y., assignor to
 Microphone Corporation of America, Brooklyn,
 N. Y., a corporation of New York

Application September 30, 1936, Serial No. 103,315

7 Claims. (Cl. 88—82)

One object of this invention is the provision of a multiple reflector adapted to be mounted on vehicles but which may, however, also be used on fixed supports such as warning signs on highways, advertising signs, etc., having the novel characteristic that the device is provided with a plurality of unitary reflector units all contained within a housing or other equivalent mounting.

Another object of the invention is the provision of a reflector constructed along the lines mentioned, which is optically efficient, simple in construction, and inexpensive in cost of manufacture.

The above and other objects will become apparent in the description below, in which characters of reference refer to like-named parts in the accompanying drawing.

Referring briefly to the drawing, Figure 1 is a plan view of one form of the reflector.

Figure 2 is a cross-sectional view taken on the line 2—2 of Figure 1.

Figure 3 is a fragmentary cross-sectional view of a modified unitary reflector element and its housing.

Figure 4 is a similar view of another modified form.

Figure 5 is a similar view of a modified form wherein the rear wall of the housing is dispensed with.

Figure 6 is a similar view of a further modified form also dispensing with the rear wall of the housing.

Figure 7 is a view taken at right angles to Figure 5, showing the reflector cup per se.

Referring in detail to the drawing, the numeral 10 indicates a housing having the front wall 11 and the rear wall 12, both being provided with mutually telescopic flanges by means of which the housing is sealed. A plurality of circular openings 13 are provided in the front wall 11, and peripheral lips 14 surround these openings.

The rear wall 12 is provided with depressions 15 which are concave on the inside of the wall, one such depression being provided for, and in axial alignment with, each opening 13. A cylindrical cup 16, open at the top, and closed at the bottom by a concave floor or base 17, is set into each concave depression 15 also in axial alignment with its opening 13. The upper rim of the cup 16 is provided with a peripheral shoulder 18. A gasket 19 of relatively soft material is mounted on the shoulder 18. Each lens 20, which is usually a sphere of red glass, is seated on the inner periphery of the shoulder 18 with the gasket 19 secured between the shoulder 18 and the lower

edge of the opening 13. The inner surface of the concave floor 17 is mirrored by means of chrome plating or in any other desirable manner. Thus, when assembled, the registering of the concave floors 17 in the depressions 15 provides fixed retention of the cups 16 in the housing. Any suitable means, such as screws passing through the walls 11 and 12, not shown, may be provided to further lock the two sections of the housings together, if desired.

In the form shown in Figure 3, similar parts are similarly numbered to that shown in Figure 2. However, in this modification, the front wall 21 of the housing is provided with openings 22 which lack the peripheral lips 14. Also, the rear wall 23 of this housing is flat throughout.

In the modification shown in Figure 4, the same housing is used as in Figure 3, but the cup 24 comprises an enlarged concave bottom 25 which serves as the mirror, and its side walls 26 are in the form of a frustoconical shell, on the upper periphery of which the lens 20 is seated.

In the modifications shown in Figures 5, 6, and 7, a single wall is used for mounting the lenses. In Figure 5, the cup 27 is provided with the peripheral flange 28. From diametrically opposite points on the flange 28, ears 29 project. The wall 30 in which the lenses 20 are mounted in this modification, is provided with openings 31 surrounded by peripheral lips 32. At diametrically opposite points at the base of the lip 32, slots are cut in the wall 30 through which the ears 29 are passed. The cup 27 is secured to the wall 30 by turning the ears 29 down against the wall. No gasket is shown in this view, although one may be used, if desired, between the cup 27 and the wall 30.

In the form shown in Figure 6, the mounting 33 is substantially similar to the front wall 11 of the housing 10. The cup 33 is provided with a peripheral flange 34 having openings at diametrically opposite points through which rivets or screws 35 are adapted to pass. A layer of relatively soft material 36, serving as a gasket, having openings therein aligned with the openings 37, is clamped between the flange 34 and the wall 38 by means of the rivets 35.

The forms shown in Figures 2, 3, and 4 are various modifications of a multiple reflector contained within a sealed housing, all of which serve the same optical purpose. The sealed housing form shown in Figure 4, however, by virtue of the greater diameter of the reflector base 25, serves to increase the useful angularity of the reflector so as to reflect light coming from a source lying

at a more acute angle to the face of the reflector.

As spherical lenses, even though manufactured to the same specification, vary considerably in their optical qualities, it is necessary to grade a large number of lenses into groups having substantially the same focal length. All of the lenses in one reflector should possess, as near as possible, the same focal length, i. e., they should each lie at the proper distance from the mirrored base. Since, however, the lenses of various reflectors will have different focal lengths, it is necessary in the forms which utilize the cylindrical cups, that the depths of these cups, or the heights or diameters of their walls 16, 21, and 33, be the same for any one reflector unit but vary as between units. In the form shown in Figure 4, such variation may be accomplished by varying the diameter of the upper peripheral opening or seat.

20 Reflectors of the type mentioned, constructed in accordance with the above description, may all be made highly efficient in optical properties, yet at the same time simple in construction and inexpensive in cost of manufacture.

25 Obviously, modifications in form and structure may be made without departing from the spirit and scope of the invention.

Furthermore, the various unitary reflector elements including the cup and its lens, are in most 30 of the forms illustrated, interchangeable with those in the other housings or mountings shown.

I claim:

1. A reflex reflector comprising a front wall having openings passing therethrough, a rear wall, a lens mounted in each of said openings, 35 cups open at the top and having concave mirrored floors, the diameter of said floors being greater than the diameter of said lenses, said cups being mounted in axial alignment with said lenses, said lenses being mounted in said openings between the inner peripheries of the openings and the upper peripheries of the cups, the bottoms of said cups resting against said rear wall, said rear wall pressing said cups against 40 said lenses and said lenses against said front wall, and means for securing said rear wall to said front wall.

2. In a multiple lens reflex reflector comprising a front wall having openings therethrough, a 50 rear wall, separate lens positioning cups having concave mirrored floors and upwardly extending peripheral walls, said peripheral walls encircling the open ends of said cups, a lens mounted in each of said openings, the front faces of said lenses projecting through said openings, the open ends of said cups being positioned over the back faces of said lenses, said lenses being positioned between the inner peripheries of said openings and the open ends of said cups, said lenses being 55 larger in diameter than said open ends of said cups and said openings, said peripheral walls of said cups positioning said lenses at a substantially focused relation to said concave mirrored floors, said cups being mounted in axial alignment with said lenses and said openings, the bottoms of said cups resting against said rear wall, said rear wall pressing said cups against 60 said lenses and said lenses against the inner peripheries of said openings, and a surrounding annular wall connecting said front and rear walls, said front and rear walls being locked together thereby locking said lenses and said mirrored cups into a focused relation.

3. In a multiple lens reflex reflector comprising 65 a front wall having openings therethrough, a

rear wall, said rear wall having seats integral with said rear wall, separate lens positioning cups having concave mirrored floors and upwardly extending peripheral walls, said peripheral walls encircling the open ends of said cups, a lens mounted in each of said openings, the front faces of said lenses projecting through said openings, the open ends of said cups being positioned over the back faces of said lenses, said lenses being positioned between the inner peripheries of said 10 openings and the open ends of said cups, said lenses being larger in diameter than said open ends of said cups and said openings, said peripheral walls of said cups positioning said lenses at a substantially focused relation to said concave 15 mirrored floors, the bottoms of said cups resting in said seats, said cups, said lenses, and said seats being in axial alignment with said openings, said rear wall pressing said cups against said lenses and said lenses against the inner peripheries of said openings, and a surrounding annular wall connecting said front and rear walls, 20 said front and rear walls being locked together thereby locking said lenses and said mirrored cups in a focused relation. 25

4. In a multiple lens reflex reflector comprising a front wall having openings therethrough, a rear wall, separate lens positioning cups, having concave mirrored floors and upwardly extending peripheral walls, each of said peripheral 30 walls having an outwardly extending rim at the open ends of said cups, said peripheral walls and said rims encircling the open ends of said cups, lenses mounted in each of said openings, the front faces of said lenses projecting through said openings, the open ends of said cups being positioned over the back faces of said lenses, said lenses being positioned between the inner peripheries of said openings and the open ends of said cups, said lenses being larger in diameter 35 than said open ends of said cups and said openings, said peripheral walls positioning said lenses at a substantially focused relation to said concave mirrored floors, said cups being mounted in axial alignment with said lenses and said openings, the bottoms of said cups resting against said rear wall, said rear wall pressing said cups against 40 said lenses and said lenses against the inner peripheries of said openings, and a surrounding annular wall connecting said front and rear walls, 45 said front and rear walls being locked together thereby locking said lenses and said mirrored cups into a focused relation. 50

5. In a multiple lens reflex reflector comprising a front wall having openings therethrough, a rear wall, separate lens positioning cups having concave mirrored floors and upwardly extending peripheral walls, said peripheral walls encircling the open ends of said cups, a lens mounted in each of said openings of said front wall, the front faces of said lenses projecting through said openings, the open ends of said cups being positioned over the back faces of said lenses, said lenses being positioned between the inner peripheries of said openings and the open ends of said cups, lens nests of relatively soft material having said lenses nested therein, said lens nests being mounted between said front wall and said cups, said lenses being larger in diameter than said open ends of said cups and said openings, 60 said peripheral walls of said cups positioning said lenses at a substantially focused relation to said concave mirrored floors, said cups being mounted in axial alignment with said lenses, said lens nests, and said openings, the bottoms of said 65 cups

5 cups resting against said rear wall, said rear wall pressing said cups against said lenses, and said lenses against the inner peripheries of said openings, and a surrounding annular wall connecting said front and rear walls, said front and rear walls being locked together thereby locking said lenses and said mirrored cups into a focused relation.

6. In a multiple lens reflex reflector comprising 10 a front wall having openings therethrough, a rear wall having seats integral therewith, separate lens positioning cups having concave mirrored floors and upwardly extending peripheral walls, said peripheral walls having outwardly extending rims at the open ends of said cups, said peripheral walls and said rims encircling the open ends of said cups, lenses mounted in each of said openings, the front face of said lenses projecting through said openings, the open ends 15 of said cups being positioned over the back faces of said lenses, said lenses being positioned between the inner peripheries of the openings and the open ends of said cups, said lenses being larger in diameter than said open ends of said 20 cups and said openings, said peripheral walls of said cups positioning said lenses at a substantially focused relation to said concave mirrored floors, the bottoms of said 25 cups resting in said seats, said cups, said lenses, said lens nests, and said seats being in axial alignment with said openings, said rear wall pressing said cups against said lenses and said lenses against the inner peripheries of said 30 openings, and a surrounding annular wall connecting said front and rear walls, said front and rear walls being locked together thereby locking said lenses and said mirrored cups into a focused relation.

ing said lenses and said mirrored cups in a focused relation.

7. In a multiple lens reflex reflector comprising 5 a front wall having openings therethrough, a rear wall having seats integral therewith, separate lens positioning cups having concave mirrored floors and upwardly extending peripheral walls, said peripheral walls having each an outwardly extending rim at the open end of the cup, said peripheral walls and said rims encircling the open ends of said cups, lenses mounted in each of said openings, the front faces of said lenses projecting through said openings, the open ends of said cups being positioned over the back faces of said lenses, said lenses being positioned between the inner peripheries of said 10 openings and the open ends of said cups, lens nests of relatively soft material having said lenses nested therein, said lens nests being mounted between said front wall and said cups, 15 said lenses being larger in diameter than said open ends of said cups and said openings, said peripheral walls of said cups positioning said lenses at a substantially focused relation to said 20 concave mirrored floors, the bottoms of said 25 cups resting in said seats, said cups, said lenses, said lens nests, and said seats being in axial alignment with said openings, said rear wall pressing said cups against said lenses and said lenses against the inner peripheries of said 30 openings, and a surrounding annular wall connecting said front and rear walls, said front and rear walls being locked together thereby locking said lenses and said mirrored cups into a focused relation.

35 MORRIS KAPLOWITZ.
